CLAIM

I claim the ornamental design for a biscuit jointer power tool, as shown and described.

DESCRIPTION

FIG. 1 is a perspective view of the biscuit jointer power tool. FIG. 2 is an opposite perspective view of the biscuit jointer power tool.

FIG. 3 is a side view of the biscuit jointer power tool.

FIG. 4 is a top view of the biscuit jointer power tool.

FIG. 5 is a bottom view of the biscuit jointer power tool.

FIG. 6 is a front view of the biscuit jointer power tool; and,

FIG. 7 is a rear view of the biscuit jointer power tool.
